UNITED STATES PATENT OFFICE.

BERNARD V. APFELD, OF SPOKANE, WASHINGTON.

SPICE-CABINET.

1,162,203.

Specification of Letters Patent.

Patented Nov. 30, 1915.

Application filed January 11, 1915. Serial No. 1,615.

To all whom it may concern:

Be it known that I, BERNARD V. APFELD, a citizen of the United States, residing at Spokane, in the county of Spokane and 5 State of Washington, have invented new and useful Improvements in Spice-Cabinets, of which the following is a specification.

My invention relates to an improved spice cabinet and has as its principal object the 10 provision of a device so arranged so that the proprietor may at all times determine the amount of stock contained therein.

A second object of my invention is to provide a device which not only gives a display 15 face but is also readily accessible for the removal of articles for sale.

A final object of my invention resides in the particular arrangement and combination of parts hereinafter described.

20 In the accompanying drawing:—Figure 1 is a perspective view of a cabinet embodying my invention. Fig. 2 is a sectional plan view taken on the line 2—2 of Fig. 1 showing the second tier of display space 25 and storage compartment. Fig. 3 is a view similar to Fig. 2 but showing the parts in different position. Fig. 4 is a sectional view taken on the line 4—4 of Fig. 3. Fig. 5 is a front elevation of the drawers shown in 30 Fig. 4. Fig. 6 is a detail view taken from the left of Fig. 5. Fig. 7 is a detail view similar to Fig. 6 but taken from the right of Fig. 5.

Throughout the separate views the same 35 part is designated by the same reference character.

Referring more particularly to the drawings, 1 is a combined storage and display cabinet made according to my invention and 40 shown placed on a counter such as 2. The cabinet 1 is provided with side walls such as 3—3 and has a vertical partition such as 4, best shown in Figs. 2 and 3, which is placed near the front thereof. The front 45 face of the cabinet is closed by a door such as 5 and the space contained between the partition 4 and the closed door 5 is divided into compartments such as 6 by means of horizontal floors such as 7. Packages of 50 spice or the like which are numbered 8 may be seen in the compartment 6 through the glass 9 of the door 5.

In the rear of the partition 4 are a number 55 of compartments such as 10 which are relatively large compared to the exhibition compartments 6. In each compartment 10

I mount a drawer such as 11 in which is stored other packages of goods 8 of the same character as those held in the display compartment on the same level with the drawer. 60 As the drawers 11 open rearwardly the salesman has ready access to the goods as soon as a package of a certain character is called for by a customer.

The drawers 11 comprise each a metal 65 bottom such as 12, metal side strips 13 which also extend around the rear end of the drawer, and metal shutter strips such as 14—14. The metal pieces 12, 13 and 14 are connected at their outer ends to a wooden 70 end piece 15, and at their inner ends to the wooden strip 16, which forms the front end of the drawer.

In order to facilitate the withdrawal of 75 a package when desired, the side walls 3—3 of the cabinet are cut away in a step formation as clearly shown in Fig. 1, and the rear ends of the drawers are left uncovered. Consequently the salesman does not have to 80 open a drawer in order to take out a package. Moreover, I provide means whereby the packages are automatically brought to the rear of the door so as to be convenient to the hand. Such means comprise a cross 85 piece 17 which is mounted within the ends of the drawers so as to slide on the strips 14 and 13 and which is connected by a spring 18 to the end piece 15. It will be seen from the foregoing that the slidable piece 17 urged by the spring 18 will 90 constantly press the packages 8 to the rear of the drawer where they can be readily obtained.

In order to facilitate the introduction of 95 the packages into the drawers I provide a spring catch 19 which is mounted so as to project forwardly through a central slot 20 in the member 17. The member 16 also is provided with a central slot 21 and when 100 the member 17 is pulled so as to extend the spring 18 to its full extent, the catch 19 will be pressed over the forward edge of the bottom of the slot 21 so as to hold the member 17 against the member 16 with the spring in extended position. If now the 105 drawer is pushed into the cabinet, to its fullest extent the upwardly inclined end 22 of the spring catch 19 will strike the inclined surface of a notch 23 hollowed out of the rear face of the member 4 and lift 110 the spring catch out of engagement with the edge of the slot 21 whereupon the pres-

sure of the spring 18 will be exerted against the packages in the drawers. It will be seen that the spring 18 is attached directly to plates 24 and 25 which are carried by the 5 members 15 and 17, respectively.

In order to facilitate the making of an inventory and to enable the amount of stock to be readily told at any time, I provide an indicator disk 30 which is pivotally mounted at the outer end or right hand end of the drawer as shown in Fig. 4. The disk 30 is numbered on its exterior as shown in Fig. 5 while its inner surface is notched as shown at 31 in Figs. 6 and 7. A spring catch 32 10 is fastened to the front of the member 15 normally holds the disk 30 from turning in any but the desired direction. A pawl 33 is provided which is pivoted at the end of a short lever 34. The pawl 33 is thrown into 15 engagement with the notched surface 31 by means of a spring member 35 which is also fastened to the front of the member 15 and which extends between the curved lower end of the pawl 33 and the face of the end 20 piece 15. The lever 34 is fixed to a shaft 35' which is journaled at the upper edge of the end piece 15 by means of suitable brackets such as 36'. Fixed to the shaft 35' are shown two arms such as 36—36 which 25 extend inwardly from the end piece 13 and partly cover the open space at the rear end of the drawer. It will be evident that the arms 36 cover the most accessible packages 30 in the drawer and that these arms must be lifted to remove one of the packages, unless the drawer should be open. If the arms 36 are thrown up into the position shown in Fig. 7 then the pawl 33 will be forced down 35 turning the disk 30. Consequently, each 40 time a package is removed from a drawer, the disk 30 is turned so as to indicate this fact. If desired, of course, the disk 30 may be numbered in the reverse direction so as to indicate the number of packages remain-

ing in the drawer instead of the number 45 which have been taken out. In order to facilitate the lifting of the arms 36 the edges of the drawers are notched as shown at 37. It will be understood, of course, that the arms 36 may be covered with a plate to 50 prevent dust from settling in the uncovered portion of the drawer.

It will be understood that while I have shown and described the preferred form of my invention, I contemplate the use of mechanical equivalents for the parts described herein wherever such substitutions may be found advantageous.

Having thus described my invention what 55 I claim is:—

1. The combination with a cabinet having at least one drawer therein, of a spring operated member slidably mounted in said drawer for forcing packages toward the outer end of the drawer, means for holding 65 said member against its spring, and means for releasing said holding means when the drawer is pushed into the cabinet its fullest extent.

2. The combination with a cabinet having 70 at least one drawer therein, of a spring operated member slidably mounted in said drawer for forcing packages toward the outer end of the drawer, means for holding 75 said member against its spring, and means for releasing said holding means when the drawer is pushed into the cabinet its fullest extent, said holding means comprising a spring catch projecting inwardly from said member and adapted to catch over the inner 80 edge of the inner end of the drawer and project inwardly therefrom.

In testimony whereof I affix my signature in the presence of two witnesses.

BERNARD V. APFELD.
